BUILDING CONSTRUCTION

George R. Collins, Kansas City, Mo.

Application April 10, 1933, Serial No. 665,428

1. Claim. (Cl. 72—77)

The present invention relates to an improved building construction, especially adapted for buildings or other permanent structures, located in areas which are subjected to earthquakes and the like.

Heretofore, irreparable damage has been done to buildings located in areas which are frequently subjected from time to time to earth disturbances such as earthquakes and the like and it is one of the objects of the present invention to provide a building construction which will overcome this difficulty.

A still further important object of the invention is to provide a structure which will positively prevent damage to buildings during earthquakes and other ground disturbances, which may be incorporated in the building during the construction thereof, or applied to an old erected building.

The present invention contemplates the provision upon the top surface of any type of foundation, of a flat, smooth metallic surface secured thereto on which there is placed a plurality of spaced ball bearings on which rests the bottom of the building which has secured on its underneath side a similar flat smooth metallic surface to the end that upon the moving, swaying, or quivering of the foundation due to an earth disturbance, such as an earthquake or the like, the building will remain in its normal upright position, undamaged or injured, from such shocks or disturbances.

Other objects and advantages, including simplicity of design, low cost of manufacture and durability, will become apparent during the course of the following description.

In the accompanying drawings, forming a part of this application, in which corresponding parts are designated by similar reference numerals,

Figure 1 is a front elevational view, partly in section of a building embodying the principle of construction of this invention.

Figure 2 is a fragmentary top plan view of a portion of a foundation showing the lower plate in position thereon,

Figure 3 is a fragmentary front elevational view partly in section of a building showing the manner in which the plates are secured to the foundation and the lower portion of a building with the ball bearings in position therebetween.

Figure 4 is a fragmentary top plan view of one form of foundation which may be employed and showing the manner in which the plates are secured thereto,

Figure 5 is a perspective view of one form of plate which may be employed,

Figure 6 is a fragmentary front elevational view partly in section of the lower portion of a building partly in section, showing a modified form of plate secured thereto,

Figure 7 is a perspective view of the plates shown in Figure 6,

Figure 8 is a fragmentary front elevational view partly in section of a building partly in section showing a further modified form of plate,

Figure 9 is a fragmentary perspective view of the type of plate used in the construction shown in Figure 8,

Figure 10 is a fragmentary front elevational view of a building partly in section showing the invention applied to a different type of building,

Figure 11 is a longitudinal sectional view of an elliptical form of bearing which may be employed.

In the accompanying drawings, wherein for the purpose of illustration there is shown preferred embodiments of the invention, and referring more particularly to Figure 1, the reference numeral 12 generally designates the foundation constructed of stone or the like, on which there is mounted in the manner illustrated, a building 14 which may be in the nature of an office building, or any type of building desired.

Upon the foundation 12 as illustrated in Figure 3, there is securely fastened a plurality of contiguously arranged, U-shaped in cross-section plates 16, by means of the screw threaded bolts 18. These plates are constructed of steel or any other hard metal. As clearly shown in Figure 3, a plate 20 of similar construction is securely fastened to the underside of the building 14 and, interposed between the opposed surfaces of the plate there are arranged a plurality of spaced ball bearings 22, the inner opposed surfaces of the plate are smooth to permit of the free rolling of the ball bearings 22. It is to be noted in this connection that the dimension of the plate and the ball bearing can be determined by the type and weight of the building construction.

On the sides of the building adjacent the plates, there is securely fastened strips 26 which cover the openings 24 between the two metallic plates 16 to 20 to prevent dust, rain, dirt and the like from going into the openings and impeding the free rolling of the balls 22 between the plates. The upstanding ball retaining arms 17 of the plate 16 are of such length as to permit of the free rolling and moving of the balls.

Upon the occurrence of an earth disturbance such as an earthquake or the like, the ground will quiver or shake and quickly move the foundation of the building to the dotted position illustrated in Figure 3 and consequently due to the inertia of the building 14 the balls 22 will freely roll on the smooth surfaces of the plates, leaving the building construction in an upright, perpendicular position during the continuance or progress of this disturbance. Earth disturbances, such as earthquakes or the like have been found, even during their greatest shocks, to move the ground not more than three or four inches and consequently the travel of the ball bearings between the plates will be only for a short distance.

Furthermore, the space between the ball bearings may be greater than the diameter of the bearings to the end that a movement of the foundation due to the earth disturbance will permit of the free rolling of the balls in any direction, without disturbing the upright position of the building.

The plates may be of any size, and as illustrated in Figure 4, may be formed of a plurality of sections which are contiguously arranged and securely fastened in position to the foundation and to the underneath side of the building, by means of screw threaded bolts 18. In order to

provide a smooth, flat surface, the apertures 30 in the plate are countersunk permitting the upper surface of the head thereof to be flush with the plane surface of the plate.

As illustrated in Figure 8 the inner surface of the plates defined by the upstanding arms 31 may be slightly curved as at 32 to present a smoother surface to permit of the balls 29 to move freely.

Or if so desired, as shown in Figures 6 and 10, the plates 38 may be perfectly flat and smooth instead of being provided with the upstanding ball retaining arms. They are secured in the same manner as the other plates by means of the screw bolts 18.

Having thus described the invention what is claimed is:

In a building construction having a foundation and a building thereon, plates secured to the upper side of said foundation, oppositely disposed plates on the underside of said building, ball bearings disposed between said plates permitting of the free movement of either said building or said foundation and a strip disposed adjacent the outside of the building over the opening between said plates for preventing the entrance of foreign elements between the plates.

GEORGE R. COLLINS.
